SINK PAD

John H. Suarez, Brooklyn, N. Y.

Application September 16, 1949, Serial No. 116,019

6 Claims. (Cl. 4—187)

1

This invention relates to pads and particularly pertains to a new and useful sink pad adapted to prevent damage to both dishware and sinks.

The dropping of dishware in a sink during the washing thereof or the handling thereof above a sink, as in the stacking of dishes in a cabinet above a sink, is not an uncommon accident and, due to the hardness of the materials with which sinks are manufactured, results almost invariably in the shattering of the dropped pieces. Often the mere placing of finer glassware in a sink is sufficient to cause chipping or the complete breakage thereof.

Also, in the cleansing of pots the use of a scouring powder is in wide practice. Included in the composition of most of said scouring powders can be found pumice or other abrasive ingredients. In time these abrasives cause the wearing away of the enamel, porcelain, or other material with which a sink may be coated. Thus there is effected a dark unsightly spot in the sink, and, as in the case of a porcelain coated metallic sink, this wearing away of the surface coating may be sufficient to permit the corrosion of the metal thereunder.

Also, the amount of grease and the like which can be accumulated on a sink's bottom during a single day can be considerable, as can be the amount of labor required to remove that grease from said sink bottom.

Therefore, one object of the present invention is to provide means whereby the breakage of dishware and glassware may be decreased considerably.

Another object of the present invention is to provide means whereby the bottom of a sink may be cushioned or padded to thus decrease dishware and glassware breakage resulting from the accidental dropping or placing thereof into a sink.

Another object of the present invention is to provide means whereby a sink bottom may be cushioned or padded without the effect of stopping-up the sink drain.

Another object of the present invention is to provide drainage means in a sink bottom cushion or pad, to thereby eliminate the possibility of accumulating water on the surface of the cushion.

Another object of the present invention is to provide means whereby a sink bottom may be protected from discoloration and corrosion due to cleansing abrasives.

Another object of the present invention is to eliminate the accumulation of grease and the like on a sink bottom.

Still another object of the present invention is

to provide a sink bottom cushion which is adaptable for utilization as a drainboard pad.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an isometric view illustrating one embodiment of the present invention.

Fig. 2 is a sectional view taken along the lines 2—2 of Fig. 1, thus facilitating the understanding of the construction of the first embodiment.

Fig. 3 is a sectional view of a sink, illustrating the contemplated employments of the present invention.

Fig. 4 is an isometric view of a second embodiment of the present invention.

Fig. 5 is a sectional view taken along the lines 5—5 of Fig. 4 and illustrates the internal construction of the second embodiment.

Fig. 6 is an isometric view of a third embodiment of the present invention.

Fig. 7 is a section taken along the lines 7—7 of Fig. 6 and shows the interior of the embodiment of Fig. 6.

The sink pad, according to the first form of the invention shown in Figs. 1 to 3, includes a pad body 10 formed, preferably by moulding, of rubber, plastic or any similar flexible material and comprises a base 11 of rectangular or any other configuration which might conform more readily with a sink bottom. As better seen in Fig. 2, a vertically extending rib 12, formed during the moulding process, is provided marginally on three sides of the said base 11. Other vertically extending ribs 13, formed by the moulding process, are also provided and are spaced apart and run longitudinally of the base 11 and may be provided with a layer of cushioning sheath 11^a of any suitable soft material. An aperture 14 is substantially centrally disposed in the base 11.

Now as seen in Fig. 3, the pad 10, when positioned in a sink 15 completely protects the bottom thereof, and, in view of the resiliency of rubber and the like in comparison with the hardness of the sink itself, affords a decidedly softer surface for dishes or glassware which might be placed or accidentally dropped into the said sink.

The afore-mentioned aperture 14 is so disposed in the base 11 as to register with sink drain 16 which permits unhampered drainage of

the sink and also prevents the shifting of the pad 10 incidental to the seepage of water thereunder. Inasmuch as the marginal rib 12 exists only on three sides of the base 11, drainage of the surface of the pad 10 is facilitated, thereby eliminating the need for raising the pad after each running of the water to prevent the accumulation of water on the surface thereof. When utilized with a sink having a drainboard 17, the pad 10, is equally useful thereon for the protection of dishware prior to the drying thereof. Here, too, it may be seen that the surface of the pad 10 will be always inclined to drain itself. Also, the above mentioned ribs 13 will facilitate stacking the dishes and prevent the dishes from sliding laterally off the drainboard 17.

The second embodiment of the pad body 10, seen in Figs. 4 and 5, provide for a quadrilateral base member 20, also of rubber, a plastic, or suitable like material, and is so formed to provide marginal and vertically extending sides 21. Said sides are provided internally with a groove 22, which groove is adapted to receive therein the edges of a top sheet 23 of similar material and configuration, and also having the longitudinal ribs 13 formed thereon. The edges of said top sheet 23 are sealed in the said groove 22 by a heating process, cementing, or other suitable means. Prior to said sealing, however, a sheet of cushioning material 24, such as sponge rubber or the like, is interposed between the said base member 20 and the top sheet 23. In the present embodiment a drain hole 25 comprises axially aligned holes in the base 20, the cushion sheet 24, and the top sheet 23, and water is prevented from seeping therebetween by a rubber sleeve 26 secured in place by the heretofore mentioned heating or cementing sealing process. This arrangement provides an even more soft cushion for dishware accidentally dropped into a sink and is employable in the same manner as the first embodiment hereinabove described.

Another embodiment is seen in Figs. 6 and 7, wherein a rectangular rubber or plastic base member 30 is provided and has formed thereon downwardly extending sides 31, which sides have internally therein a groove 32. On the upper side of said base member 30 and on three of the marginal edges thereof, there is formed a vertically extending rib 33. Other vertically and longitudinally extending ribs 13 are formed in a spaced apart relation on the upper surface of the base member 30.

An under-sheet 34 of like material and configuration has formed therein several spaced rows of concavities or recesses 35, which recesses are shaped to receive cylinders 36 of sponge rubber or similar resilient material. The edges of said under-sheet 34 are disposed in the said groove 32 and are sealed therein by means of a heating or similar process; and, when so sealed, it is seen that the said cylinders 36 are interposed between the said base member 30 and the under-sheet 34. Also, as in the above described embodiment, a drain hole 25 is provided, but in the present arrangement it comprises axially aligned apertures in only the base member 30 and the under-sheet 34. Water is prevented from seeping between the base and the under-sheet by a rubber sleeve 26 which is secured in place during the mentioned sealing process.

The present arrangement when positioned in a sink in the manner seen in Fig. 3 has the drain hole 25 in register with the sink drain 16. This

assures proper drainage of the sink, which is also aided by convexities 37 formed on the under-side of the under-sheet 34 for permitting a flow of water beneath the pad and to said sink drain. The mentioned marginal ribs 33 on the three sides of the base 30 permit a drainage of water off the surface, in the manner above mentioned with regard to the other embodiments.

Whereas, in the second described embodiment 10 the sponge rubber was in sheet form and provided a cushion to dishware dropped anywhere on the pad 10, it will be understood that the present embodiment, though employing only cylinders 36 of sponge rubber, provides an equal amount of protection. If a dish were dropped on the base 30 directly above a cylinder 36, said cylinder would absorb the shock. If, however, a dish is dropped on an area of the base 30 between cylinders 36, that area absorbs the shock and conveys it to the adjacent cylinders 36 between which it is suspended. Therefore, it will be seen that although less sponge rubber is utilized in the present embodiment, it is equally effective as the described second embodiment.

In all of its above embodiments the pad body 10 affords protection to the bottom of the sink 15 against the abrasives included in scouring powders. This is so since, when employed, said pad is interposed between the sink bottom and the pots which are being scoured. Also, the grease which normally would accumulate on the sink bottom does so on the pad body 10, from which it is more readily removed.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A sink pad comprising a substantially quadrilateral flexible base, a flexible under-sheet having a plurality of concavities formed therein, said under-sheet being sealed to said base, and a plurality of cushioning members being disposed in said concavities and between said under-sheet and base.

2. A sink pad comprising a substantially rectangular rubber base having downwardly extending sides, a rubber under-sheet having a plurality of concavities formed therein, said under-sheet being sealed to said base at said downwardly ending sides, and a plurality of resilient members disposed in said concavities and interposed between said under-sheet and base.

3. A sink pad comprising a substantially rectangular rubber base having downwardly extending sides and a groove formed internally in said sides, a rubber under-sheet having a plurality of recesses formed therein, the marginal edges of said under-sheet being sealed in said groove in said base sides, a plurality of sponge rubber cylinders disposed in said recesses and interposed between under-sheet and base; and a vertically extending rib formed marginally and integrally on three sides of the upper surface of said base.

4. A sink pad comprising a substantially rectangular rubber base having downwardly extending sides and a groove formed internally in said sides, a rubber under-sheet having a plu-

rality of recesses formed therein, the marginal edges of said under-sheet being sealed in said groove in said base sides, a plurality of sponge rubber cylinders disposed in said recesses and interposed between under-sheet and base; and a vertically extending rib formed marginally and integrally on three sides of the upper surface of said base and axially aligned apertures in said base and under-sheet and disposed for registry with a drain in a sink bottom.

5. A sink pad comprising a substantially rectangular rubber base having downwardly extending sides and a groove formed internally in said sides, a rubber under-sheet, a plurality of spaced rows of concavities in the upper surface of said under-sheet, a plurality of convexities on the underside of said sheet and corresponding to said concavities, the marginal edges of said under-sheet being sealed in the groove in said base sides, a plurality of sponge rubber cylinders disposed in said concavities and interposed between said under-sheet and base, a vertically extending rib formed marginally and integrally on three sides of the upper surface of said base, and axially aligned apertures in said base and under-sheet and disposed for registry with a drain in a sink bottom.

6. A sink pad comprising a substantially rectangular rubber base having downwardly extending sides and a groove formed internally in said sides, a rubber under-sheet, a plurality of spaced rows of concavities in the upper surface of said under-sheet, a plurality of convexities on the

underside of said sheet and corresponding to said concavities, the marginal edges of said under-sheet being sealed in the groove in said base sides, a plurality of sponge rubber cylinders disposed in said concavities and interposed between said under-sheet and base, a vertically extending rib formed marginally and integrally on three sides of the upper surface of said base, and axially aligned apertures in said base and under-sheet and disposed for registry with a drain in a sink bottom and a rubber sleeve fitted in said apertures and sealed to said base member and under-sheet.
